UNITED STATES PATENT OFFICE

2,426,105

BROKEN ELECTRODE RETRIEVING MEANS

Steve W. Kemock, Chicago, Ill.

Application June 19, 1944, Serial No. 541,019

2 Claims. (Cl. 294—111)

1

This invention relates to new and useful improvements in means for removing from electric furnaces, broken electrodes and other articles in a convenient and safe manner.

The principal object of the present invention is to provide a retrieving device in the form of tongues which can be pushed into an electric furnace for the purpose of seizing broken electrodes and other articles therein and removing the same, without the necessity of first permitting the furnace to cool down.

Other objects and advantages of the invention will become apparent to the reader of the following description.

In the drawings—

Figure 1 is a fragmentary sectional view of an electric furnace and showing in top and fragmentarily, the retrieving means.

Figure 2 is a side elevational view of one modification of the retrieving means.

Figure 3 is a fragmentary top plan view showing the tongs of the retrieving means.

Figure 4 is a fragmentary elevational view of one of the jaws of the retrieving tongs.

Figure 5 is a fragmentary detailed sectional view of a further modification of the retrieving means.

Figure 6 is an enlarged cross-sectional view taken on the line 6—6 of Figure 5.

Referring to the drawings wherein like numerals designate like parts, it can be seen that numeral 5 denotes an electric furnace having a charging door opening 6.

For the purpose of retrieving broken electrodes or like objects from the inside of the furnace 5 a retrieving device generally referred to by numeral 8 is provided which is mounted on the head 11a. This head is similar to the conventional charging box head by means of which a charging box is carried on a standard charging machine.

The usual type of charging machine, for instance, the type used in connection with electric furnaces, comprises a trolley and a car for moving the equipment towards and away from the furnace or in front of the furnace respectively. This machine comprises a ram, pivotally supported on said car which may be lifted and lowered and which can be rotated around its own axis, a movement usually called "twisting" of the ram.

The ram of this machine is used to carry the device described below performing the retrieving operation. The charging machine with its trolley and car has however not been shown as it is well known in the art.

2

The ram of the charging machine is designated in the drawing by the reference numeral 9. It is supported by a frame 10a provided with a pivot 10b which in its turn is supported by a frame 10 fixed on the car.

The electrode retrieving device is mounted on a head 11a the construction of which is practically the same as that of the head of a conventional charging box. It comprises a projecting square support member 12 into which the square head of ram 9 fits and is held by a lock rod 12a.

The head 11a carries a frame structure 11 on which grapple arms 14, 14 are pivoted near their ends, by means of pivots 15. The ends of the arms 14, 14 projecting beyond the pivots 15 are connected by pivoted links 16 to a block 17. Said block is provided with an opening through which a pin 18 passes having a thickened head 18a at

one end and an eye 19 at its opposite end. A chain 20 is fastened to the eye 19 on one side and to a cable 21 on the other side and said cable is wound on a pinch 31 which is mounted on the frame 10 supported by the car.

The outer or gripping ends of the arms 14 are provided with removable jaws 22 preferably equipped with gripping spurs, knife edges, teeth or other protuberances 23 facilitating the gripping of the electrodes.

The plane in which the grapple is arranged and in which the grapple arms move is inclined with respect to the longitudinal axis of the ram and the inclination may be such that said longitudinal axis passes through a line connecting the pivots as shown in Figure 5. The fixed point on the grapple facilitates the operation for the operator standing at a remote point.

During a retrieving operation, the retrieving device is mounted on the ram in place of the charging box and may be lowered, lifted and tilted by means of the ram.

As will be clear the grapple may not only assume any desired height above the bottom and follow the inclination of the ram but may, by using the so-called twisting movement of the ram, also be brought into such inclined positions that it may seize a broken electrode whatever its position within the furnace.

The details of the operation of the grapple will be clear from the foregoing description.

While the foregoing specification sets forth the invention in specific terms, it is to be understood that numerous changes in the shape, size and materials may be resorted to without de-

parting from the spirit and scope of the invention as claimed hereinafter.

Having described the invention, what is claimed as new is:

1. A device for retrieving broken electrodes from electric furnaces, adapted to be attached to the ram of a charging machine, mounted for a swinging movement and for a twisting movement around its longitudinal axis on the said machine, comprising a head, a coupling means for detachably fixing it on the ram, a frame carried by said head, a grapple structure carried by said frame, said frame and grapple being arranged substantially within a plane inclined with respect to the longitudinal axis of the ram, said grapple structure consisting of two grapple arms pivoted on said frame and provided with gripping jaws at one end, and means including links pivoted to the grapple arms, and a centrally arranged member for controlling the gripping movement of said grapple arms and jaws from a distance. 15

2. A device for retrieving broken electrodes from electric furnaces adapted to be attached to the ram of a charging machine, mounted for a swinging movement and for a twisting movement around its longitudinal axis on the said machine, comprising a head, a coupling means for detachably fixing it on the ram, a frame carried by said head, a grapple structure carried by said frame, 20

10 said frame and grapple being arranged substantially within a plane inclined with respect to the longitudinal axis of the ram, said grapple structure consisting of two grapple arms, a pivotal connection for each of said arms on said frame, the longitudinal axis of the ram passing between said pivotal connections of the grapple arms, gripping jaws on one end of said grapple arms, pivoted links arranged on the other end of the same, a centrally arranged member pivoted to said links, and traction means attached to said member operated from a distance for moving the grapple arms.
